Primary Examiner — Jennifer L Watkins

Assistant Examiner — Samantha Lynne Brodowski

(57) **CLAIM**

The ornamental design for a shoulder/hand bag, as shown and described.

DESCRIPTION

1. Shoulder/hand bag

FIG. 1.1 is a perspective view of a shoulder/hand bag according to one embodiment of the claimed design; FIG. 1.2 is a front elevational view of the shoulder/hand bag shown in FIG. 1.1;

FIG. 1.3 is a rear elevational view of the shoulder/hand bag shown in FIG. 1.1;

FIG. 1.4 is a left side elevational view of the shoulder/hand bag shown in FIG. 1.1;

FIG. 1.5 is a right side elevational view of the shoulder/hand bag shown in FIG. 1.1;

FIG. 1.6 is a top plan view of the shoulder/hand bag shown in FIG. 1.1;

FIG. 1.7 is a bottom plan view of the shoulder/hand bag shown in FIG. 1.1.

The broken lines showing a top handle and a shoulder strap depict portions of the article and form no part of the claim. The broken lines shown on claimed surfaces depict stitching and form a part of the claim.

1 Claim, 7 Drawing Sheets
